SORTING TRAY

Irving I. Kassoy, Bronx, N. Y.

Application June 12, 1953, Serial No. 25,477

Term of patent 7 years

(Cl. D58—13)

To all whom it may concern:

Be it known that I, Irving I. Kassoy, a citizen of the United States, residing in the Borough of Bronx, county of Bronx, and State of New York, have invented a new, original, and ornamental Design for Sorting Tray, of which the following is a specification, reference being had to the accompanying drawing, forming a part hereof.

Figure 1 is a top plan view of a sorting tray, showing my new design;

Figure 2 is a bottom plan view thereof showing the tray after being swung about a transverse axis from left to right;

Figure 3 is a longitudinal cross-sectional view taken on the line 3—3 of Figure 1; and

Figure 4 is a transverse cross-sectional view

taken on the line 4—4 of Figure 1 or on the line 4—4 of Figure 2.

I claim:

The ornamental design for a sorting tray, as shown.
